UNITED STATES PATENT OFFICE.

JOSEPH B. STRAUSS, OF CHICAGO, ILLINOIS.

ELEVATED RAILWAY.

1,425,805.

Specification of Letters Patent. Patented Aug. 15, 1922.

Application filed November 4, 1921. Serial No. 512,721.

To all whom it may concern:

Be it known that I, JOSEPH B. STRAUSS, a citizen of the United States, residing at Chicago, in the county of Cook and State of Illinois, have invented a certain new and useful Improvement in Elevated Railways, of which the following is a specification.

This invention relates to elevated structures, and has for its object to provide a new and improved structure of this construction particularly adapted for elevated railways, and which can be made and installed at a much lower cost than the structures now in use, and which will at the same time be strong, durable and efficient.

Referring now to the accompanying drawings—

Fig. 1 is a side elevation of one form of structure embodying the invention;

Fig. 2 is a plan view of the device shown in Fig. 1;

Fig. 3 is an enlarged sectional view taken on line 3—3 of Fig. 1;

Fig. 4 is an enlarged view through one of the girders showing a car in position;

Fig. 5 is an enlarged sectional view taken on line 5—5 of Fig. 4, with the truck and car omitted;

Fig. 6 is a sectional view taken on line 6—6 of Fig. 4 with the motor and car omitted;

Fig. 7 is an enlarged sectional view showing the rail support and connection;

Fig. 8 is a sectional view taken on line 8—8 of Fig. 3;

Fig. 9 is a sectional view taken on line 9—9 of Fig. 3;

Like numerals refer to like parts throughout the several figures.

Referring now to the accompanying drawings, I have shown one form of elevated structure embodying the invention and particularly adapted for elevated railways. In this construction there is provided a series of central posts 1. These posts are made up of skeleton metal upright members 2 and cross members 3, which are connected together to form a skeleton post. These posts are then fastened to suitable bases.

These bases may be arranged in any desired manner. I prefer to use for each base the separated piers or supports 4, which preferably incline from the bottom to the top, and which provide a space 5 between them wherein sewers and conduits for electric wires and gas pipes, etc. may be located.

These bases are preferably made of reinforced concrete. A cross piece 6 connects these supports, and is also preferably made of concrete. This cross piece is provided at 60 the point where the posts are to be connected therewith, with the exterior plates 7, which preferably extend all around the cross piece. Rods or bolts 8 are connected with the cross piece.

The posts are provided with enlarged lower ends 9, which have engaging parts for the bolts 8, and by means of which the posts are removably attached to the cross pieces of the base. By means of this construction the bases may be first made up and then the skeleton posts attached thereto. These skeleton posts are provided with enlarged heads 10, and after the metal skeleton posts are placed in position they may be 75 filled with concrete 10^a so as to form reinforced concrete posts.

Mounted upon these central posts are the separated concrete girders 11. These are made up of skeleton metal members 13, 13^a 80 14. The skeleton metal members may be first erected, and then filled with concrete so as to form reinforced concrete girders. These girders have open spaces between them, and they are connected at intervals by 85 vertical concrete diaphragms 15 and horizontal diaphragms 16 (see Fig. 5), the diaphragms preferably being unitary with the concrete girders and also preferably located at the ends of the girders. Connected with 90 the girders 11, and projecting therefrom at intervals are cantilever brackets 17. These cantilever brackets are preferably located opposite the vertical diaphragms 15, and the brackets on one side are connected across 95 to the opposite girder by the metal connecting pieces 18. Means are thus provided for transmitting the load of each track carried by the cantilever arm, to the girder adjacent thereto and also to the other girder. 100

The brackets 17 have the cantilever members 20 and 21, upon which are carried the rails 22 of the track. The ends of these cantilever members are opposed to each other, but are separated by a space, and 105 there are guard rails 23 near the ends of these members. Above the rails 22 is a space or passage 24. Mounted on the rails 22 so as to run along in the space 24, are trucks 25, upon which are suspended the 110 cars 26. These trucks are operated by any suitable motor, such as the electric motor

27, such motor having contact devices 28 which run along the conductor 29, connected in the electric circuit. The current goes from the conductor 29, through the motor 5 to the rails 22, and then back to the source of electric supply.

The cars 26 which are suspended beneath the cantilever arms, have guides which may be rollers 30, which engage the longitudinal members 31. These longitudinal members extend along beneath the two cantilever members, and in addition to strengthening the structure, act as guides for the cars. It will be noted that the rollers or engaging parts 30 which engage these guides are at the top of the car.

Referring now to the rails 22 and associated parts it will be noted that the members or sleepers 20 have on opposite sides 20 thereof, the angles 32, and that the bolts 33 pass through these sleepers and these angles and the guide rail 23 and the plate 34 (see Fig. 7).

It will be seen that with this construction 25 the skeleton steel work of the posts and of the girders may be erected, and the concrete then later placed in position. By means of this construction the cost per mile of an elevated structure is very greatly reduced, 30 and at the same time a durable, strong, safe and efficient elevated structure is produced.

I have set forth in detail a particular construction embodying the invention but it is of course evident that the parts may be 35 varied in many particulars, without departing from the spirit of the invention as set forth in the claims hereto appended, and I therefore do not limit myself to the particular construction shown.

40 I claim:

1. An elevated structure comprising a series of central posts in substantial alignment, two separated substantially parallel girders mounted on said posts, and track 45 supporting parts extending laterally and outwardly from each girder for supporting tracks for cars, the ends of said track supporting parts being free.

2. An elevated structure comprising a series of central posts in substantial alignment, two separated substantially parallel girders mounted on said posts, cantilever 50 brackets extending outwardly from each of said girders, and tracks carried thereby.

55 3. An elevated structure comprising a series of central posts in substantial alignment, two separated substantially parallel girders mounted on said posts, cantilever brackets extending outwardly from each of 60 said girders, and tracks carried thereby, said brackets having an inverted U-shape, the tracks being located near the bottom of the opening in the U.

65 4. An elevated structure comprising single central posts, two separated substan-

tially parallel girders carried by said posts, two sets of tracks one on each side of the pair of girders, and means for transmitting the load of each track to the girder adjacent thereto and also to the other girder.

70 5. An elevated structure comprising single central posts, two separated substantially parallel girders carried by said posts, two sets of tracks one on each side of the pair of girders, projecting parts connected 75 with said girders and supporting said tracks, the load of the track on one side being transmitted to the two girders, one acting in one direction and the other acting in the other direction.

80 6. An elevated structure comprising a series of metallic skeleton posts in substantial alignment, said posts having separated, corner, skeleton, metal, upright members and skeleton connecting metal members 85 connecting said upright members together, two sets of substantially parallel separated girders, the girders carried by said posts, and concrete added to said posts and located inside the tracks carried thereby to complete 90 the same after they have been erected.

7. An elevated structure comprising a series of posts in substantial alignment, two sets of separated concrete girders carried by 95 said posts, concrete diaphragms connecting said girders at intervals, track supporting parts projecting on the outside of said girders, and tracks mounted thereon.

8. An elevated structure comprising a series of central posts in substantial alignment, two sets of substantially parallel separated girders carried by said posts, supporting 100 brackets connected with said girders at intervals and projecting outwardly therefrom, stringers mounted on said brackets, 105 cross pieces supported by said stringers, and rails on said cross pieces.

9. An elevated structure comprising a series of posts in substantial alignment, two sets of separated longitudinal girders 110 mounted on said posts, concrete bases for said posts, made separate from the posts, and means for attaching said posts to said bases.

10. An elevated structure comprising a 115 series of posts in substantial alignment, two sets of separated longitudinal girders mounted on said posts, concrete bases for said posts, made separate from the posts, means for attaching said posts to said bases, 120 and means associated with said bases to prevent uplifting.

11. An elevated structure comprising a series of central posts, two separated sets of concrete girders carried by said posts, and 125 concrete diaphragms cross connecting the end panels of said sets of girders.

12. An elevated structure comprising a series of central posts in substantial alignment, a track supporting structure support- 130

ed on said posts, a track thereon, a truck on said track, a car suspended from said truck, and guiding devices at the top of the car engaging the track supporting structure.

5 13. An elevated structure comprising a series of posts, two sets of substantially parallel skeleton separated girders carried by said posts, and concrete added to said skeleton girders to complete the same after they 10 have been erected.

14. An elevated structure comprising a series of posts, girders mounted on said posts, a base for said post comprising two separated supports, a cross piece between 15 the supports, and means for connecting the posts with said connecting pieces.

15. An elevated structure comprising a series of central posts, two separated sets of concrete girders carried by said posts and 20 having an open space between them, and concrete diaphragms extending across said open space, and connecting said girders at intervals, the remaining portion of the space between the girders being left open.

25 16. An elevated structure comprising a

series of central posts, two separated girders carried by said posts, cantilever brackets extending outwardly from each of said girders, and means for transmitting the lateral stresses to the central posts without the necessity of truss bracing. 30

17. An elevated structure comprising a series of posts, separated rails, said separated rails mounted on opposed cantilever members with a space between them, and 35 connections from said cantilever members to said posts.

18. An elevated structure comprising a series of posts, separated rails, said separated rails mounted on opposed cantilever 40 members with a space between them, and connections from said cantilever members to said posts, and guard rails for said rails, said guard rails mounted upon the opposed 45 separated ends of said cantilever members.

Signed at Chicago county of Cook and State of Illinois, this 31st day of October, 1921.

JOSEPH B. STRAUSS.
